UNITED STATES PATENT OFFICE.

CLAUDE D. ENOCHS, OF LA CROSSE, WISCONSIN, ASSIGNOR TO THE VOTE-BERGER CO., A CORPORATION OF WISCONSIN.

SELF-RESTORING CLEAR-OUT DROP FOR TELEPHONE-SWITCHBOARDS.

No. 921,384.

Specification of Letters Patent.

Patented May 11, 1909.

Application filed April 30, 1906. Serial No. 314,461.

To all whom it may concern:

Be it known that I, CLAUDE D. ENOCHS, a citizen of the United States, residing at La Crosse, in the county of La Crosse and State of Wisconsin, have invented a new and useful Self-Restoring Clear-Out Drop for Telephone-Switchboards, of which the following is a specification.

My invention relates to improvements in self-restoring clear-out drops for telephone switchboards and has, among its objects, to provide improved means for automatically restoring the drop shutter, simplicity of construction and effectiveness in use.

15 In the accompanying drawings forming part of this specification, Figure 1 is a side elevation, partly in section, of my invention; Fig. 2 is a view looking at the bottom of the keyboard and showing the cord partly broken away; Fig. 3 is a front view showing the plug and cord partly broken away, and Fig. 4 is a detail side elevation.

20 In the drawings A represents a portion of a keyboard, on which is suitably mounted an electromagnet B, head block C of a drop and self-restoring mechanism D for the shutter on the drop. As shown, the magnet is provided with an armature 2, which is pivotally carried by a yoke 3, which in turn is removably fastened to the shell 4 of the magnet by means of spring catches 5. The armature carries a latch 6, which extends forward over the magnet shell to normally hold the shutter 9 closed. The purpose of detachably supporting the yoke on the shell is to provide means whereby the armature may be detached and the coil within the shell removed when desired.

25 The shutter 9 is pivoted in the usual manner, as at 8, upon the front of the head block and is provided with an indent 7 on its inner face for the retention of the shutter in position by means of the latch. This construction causes the shutter to normally cover the end of the latch 6 from view in front. The shutter is provided with an inturned tongue 10, which projects into the chamber 11 in the head block.

30 The self-restoring mechanism includes a plug seat 12 formed by a bracket which is suitably fastened to the keyboard and by a socket 13 passing vertically through said keyboard. Passing across said bracket is a lever 14, one end of which is pivoted at 15 by 35 a suitable support upon the keyboard and

the other end loosely connected at 16 to a trigger arm 17, which loosely engages the tongue 10 on the shutter and passes through an opening 18 in the keyboard. At the back of the head block C is a plate 19, which is 40 provided with a loop 20. A tractile spring 21 has its ends connected one to the loop 20 and the other to the trigger end of the lever 14. The lever 14 and plug seat 12 have openings 22 through which the connecting 45 cord 23 plays freely, the opening through the lever being of sufficient size to prevent the cord touching it when twisted or bent about the keyboard. One end of the cord is connected with the usual plug 24 and its other 50 end with the switchboard mechanism in the customary manner. Between the ends of the cord a weighted pulley 25 is freely disposed.

55 In operation, when the plug is raised from the plug seat to make a connection, the spring 21 raises the lever 14 with its trigger above the tongue 10. When the shutter drops the plug is returned to its seat, the pulley 25 carrying it into its seat and depressing the lever 14. This operation lowers the trigger and automatically restores the shutter into engagement with the latch 6.

60 It is obvious that the construction above set forth may be changed and varied without departing from the spirit of this invention, and I do not limit or confine myself to the exact construction described.

65 Having described my invention, what I claim as new and desire to protect by Letters Patent, is:—

1. A drop including a head block, a shutter pivotally supported on said block, having an in-turned tongue, a key board, a weighted cord and plug passing through said board, a lever actuated downwardly by the weight of said plug, and having an opening through which said cord loosely plays, means for moving said lever upwardly, a seat below said lever having an opening through which said cord passes, and a trigger carried by said lever and adapted to engage said tongue to restore said shutter.

105 2. A drop including a head block, a shutter pivotally supported by said block, having an in-turned tongue, an indent on its inner face, a latch bar to engage said indent, said shutter normally covering the end of said latch bar from view in front, a frame, a weighted cord and plug passing through said 110

frame, a lever pivoted upon said frame, actuated by the weight of said plug and having an opening through which said cord loosely plays, and a seat on said frame below said lever having an opening through which said cord passes.

3. A device of the class set forth, comprising a drop having a pivoted shutter provided with an inturned tongue, a head block suitably chambered to receive said tongue, a trigger projecting into said head block and adapted to engage said tongue for restoring said shutter, an up-pressed lever carrying said trigger, a seat below said lever, a weight-
- 10

ed cord and plug, and a suitable frame for supporting said parts, said frame, lever and seat provided with an opening through which said cord is free to play, said plug adapted normally to rest upon said lever to cause said trigger to restore said shutter.

In testimony whereof I have signed my name to this specification in the presence of two subscribing witnesses.

CLAUDE D. ENOCHS.
